UNITED STATES PATENT OFFICE

WILLIAM S. PARKER, OF LAINGSBURG, MICHIGAN.

MIDDLING-PURIFIER.

SPECIFICATION forming part of Letters Patent No. 367,116, dated July 26, 1887.

Application filed July 29, 1886. Serial No. 209,427. (No model.)

To all whom it may concern:

Be it known that I, WILLIAM S. PARKER, a citizen of the United States, residing at Laingsburg, in the county of Shiawassee and State 5 of Michigan, have invented certain new and useful Improvements in Middlings-Purifiers; and I do hereby declare the following to be a full, clear, and exact description of the invention, such as will enable others skilled in the 10 art to which it appertains to make and use the same.

The object of this improvement is to provide a middlings-purifier of simple and economical construction and rapid and efficient 15 operation. These results are attained by the mechanism illustrated in the drawings here-with filed as part hereof, in which the same letters of reference denote the same parts in the different views.

20 Figure 1 is a plan representing a bolting and purifying machine embodying my improvement. Fig. 2 is a partially sectional side elevation of the same. Fig. 3 is a transverse section taken on the line $x-x$ of Fig. 2. Fig. 25 4 is a detail plan view of one of the sieves, with parts removed that are fully shown in other figures. Fig. 5 is a transverse vertical section of the same taken centrally. Fig. 6 represents an inverted section thereof. Fig. 7 is a 30 sectional detail representation.

A is the supporting and inclosing frame, consisting of suitably-connected upright and transverse beams, as more fully shown in Figs. 2 and 3.

35 A' A² are the top and floor of the same.

B B' B² B³ represent doors secured to the upright frame-pieces by means of hinges b b b b.

The upright frame-pieces are made to support a series of circular sieve-frames, 1 2 3 4, 40 one above the other, as hereinafter explained.

45 These sieve-frames carry sieves of different texture, the upper one being the coarsest, the next being finer, and the lowest being the finest and of a texture adapted to operate as a purifier.

As fully shown in Figs. 3, 4, 5, the sieve-frames are each composed of a frame, C, a transverse rib, d, an inner frame, C', transverse pieces c c', suitably secured to the frames C 50 C' by screws or otherwise, as indicated at c², and with a central perforation, c³, for a pur-

pose hereinafter set forth. The sieve-screens C² are secured to their respective frames by means of circular frames C³, fixed to the frames C C' by screws c⁴, as shown in Fig. 6, 55 or by other suitable or additional means, as may be deemed advisable.

D is a section of the driving-shaft located at the vertical center of the frame A, and loosely fitted in the perforations c⁵ of the sieve-frames, and provided at its lower end with a suitable bearing fixed to the floor A' of the 60 inclosure.

D' is a pulley for the shaft D.

E represents metal segments or plates fixed 65 by rivets or otherwise to the sieve-frames at equidistant points and having integral projections provided with rollers F, secured in their positions thereon by riveting or otherwise, substantially as shown at f f. The sieve- 70 frames are supported in the positions shown by bars fixed horizontally to the upright frame-pieces A, as shown at a, which form bearings for the rollers F.

G is a vertical shaft having at its lower end 75 a metal bearing, g, fixed to the floor A² of the inclosure, from which it extends through the top of the same sufficiently to be provided with a pulley, g', in line with the pulley D' on the shaft D.

80 G' G² G³ G⁴ represent curved portions or cranks made integral with or fixed to the shaft G in positions adjacent to and in line with the sieve-frames 1 2 3 4. Each of the sieve-frames is provided, in the positions 85 shown in Fig. 3, with a plate, H, having a curved projection, h, at one end, and a plate, H', having opposite projections, h' h², for a purpose hereinafter explained.

The plates H H' are riveted or otherwise 90 fixed to the sieve-frames.

K is a light spring, bolted, as shown at k, to the inclosure-wall B⁴, immediately opposite each of the plates H, and extended thence in a manner adapted to engage with the projections h of the plates H.

L is a light spring, bolted, as shown at p, to the door B, immediately opposite each of the plates H, and extending thence in a manner to engage the projections h² of the plates H', the 100 parts h' of which project therefrom sufficiently to be engaged by the arms of the shaft G, as

indicated at G^2 . The shafts G and D are connected by a belt, P . (Shown in Fig. 1.)

$R R R$ represent brushes made either of fine steel wire, bristles, or other suitable material, and secured to the shaft D in positions for suitably engaging with the sieves of the sieve-frames 1, 2, 3, and 4.

The shaft D may be provided with an additional brush suitable for engaging with the 10 sieve of the sieve-frame 4, if deemed advisable. The brushes are secured to the shaft D by means of straps R' , fixed thereto by bolts and adapted to fit the shaft, as shown in Fig. 7. The straps R' are arranged to movably fit the 15 shaft D , and are provided with set-screws $S' S'$, by means of which the brushes may be rigidly but adjustably secured in position adapted for suitable engagement with the texture of the sieves.

20 The stock is introduced into the upper sieve through a conduit S . The shaft D is put in motion by a pulley. (Not shown.) Motion is communicated to the shaft G , in the direction of the arrow shown in Fig. 3, through the belt 25 P , connecting the pulleys D' and g' . When in motion, the cranks $G' G^2 G^3 G^4$ of the shaft G will engage the projections h' of the plates H' , fixed to the sieve-frames, and the projections h^2 of the plates H' will be driven against their 30 corresponding springs, L , fixed to the door B . When the cranks of the shaft G pass the plate projections h' , the springs L will impart quick reverse motions to the series of sieve-frames, which, by reason of being mounted on 35 the rollers F , will be easily moved, and the force of the springs L will cause the projections h of the plates H to engage with the springs K , fixed to the wall B' , and the springs L and K will cause a forcible shaking of the 40 sieve-frame that will cause the rapid passage of the flour through the sieves, which operation will be additionally facilitated by the brushes R , which will revolve with the shaft D , and by engaging with the entire texture of

the sieves prevent the same from clogging. 45

The shaking of the sieve-frames, as described, will cause the lighter and inferior elements of the stock to work upward and a tendency to accumulate at the transverse ribs d . The mechanism is to be provided with a suction-fan arranged to communicate through the floor A' with the sieve-frames through their central openings and draw off the lighter and inferior elements of the stock as they are separated from the flour, which will become more and more purified as it passes from one sieve to another. 50 The lowest sieve-frame is provided at one side with a spout, (shown at Q in Fig. 2,) and through which the valuable inferior elements reaching the sieve through those above will be exhausted, and may be directed, as desired, through a suitably-arranged conduit communicating with the spout Q .

By reason of the walls $B B' B'' B'''$ being hinged to the uprights of the frame, the interior parts 55 of the mechanism are conveniently accessible for removal and repair or other purposes, as occasion may require.

Having thus described my invention, what I claim as new, and desire to secure by Letters Patent, is—

An improved middlings-purifier, comprising the supporting-frame provided with bars a , and having the hinged doors $B B' B'' B'''$, the shaft D , the sieve-frames 1.2.3.4, provided 75 with rollers F and plates $H H'$, the brushes R , having straps R' for adjustably holding them upon the shaft D , the shaft G , having cranks G' for engaging the plates $H H'$, and the springs $K L$ for returning said sieve-frames when 80 struck by the cranks, substantially as described.

In testimony whereof I affix my signature in presence of two witnesses.

WILLIAM S. PARKER.
